ATTORNEY.

UNITED STATES PATENT OFFICE.

THOMAS B. JOHNSON, OF LULING, TEXAS.

WIRE FENCE.

SPECIFICATION forming part of Letters Patent No. 596,003, dated December 21, 1897.

Application filed September 7, 1897. Serial No. 650,782. (No model.)

To all whom it may concern:

Be it known that I, THOMAS B. JOHNSON, a citizen of the United States, residing at Luling, in the county of Caldwell and State 5 of Texas, have invented certain new and useful Improvements in Wire Fences; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 The special object of my invention is to make a cheap and efficient post to which fence-wires may be quickly and durably stapled.

Reference is made to the accompanying drawings, in which—

20 Figure 1 is an elevation of a fence embodying my invention, and Fig. 2 a back detail and section of one post.

In the drawings, A represents the wire rails, B the posts to which they are attached, and 25 C the staples by which the rails are secured to the posts.

I preferably cast the posts B with tubular bodies b, solid points b', a vertical slot b², and the lateral notches b³; but they may be made 30 of malleable metal or of a solid bar doubled or folded in the middle, so as to bring together the ends, which are made to form a point. The staples C have their legs c c extended through the slot b², where a rail is to

go, and then bent in opposite directions, so 35 as to rest in the notches b³, thus leaving the loop c' and the turned ends of the legs on opposite sides of the post. The rails A are passed through the loops c' of the staples and are pulled by the staple slightly into the slot 40 b², thus making a small dent in the wire at each post before the legs c c are clenched, so as to have their ends lying in the post-notches b³. This causes all the slack in the wire to occur at the posts, where it may be easily 45 taken up; but in practice the wire will rarely slack to any considerable extent where the drive-posts B are firmly planted. The single slot b² is better than separate ones for each rail, because it enables the fencer to readily 50 place his wire rails at any preferred distance apart, while my way of clenching the staples prevents them from drawing out, as they do in wooden posts.

What I claim as new, and desire to protect 55 by Letters Patent, is—

A metallic post, for wire-rail fences, provided with the tubular body b, vertical slot b², solid point b', and cross-notches b³ whereby it may be used with staples and wire rails 60 in the manner and for the purpose set forth.

In testimony whereof I affix my signature in presence of two witnesses.

THOS. B. JOHNSON.
